Inventor
David Hindahl,
By Wilkinson, Hussey, Bryan & Knight Atto.

UNITED STATES PATENT OFFICE

DAVID HINDAHL, OF CHICAGO, ILLINOIS, ASSIGNOR TO RODGER BALLAST CAR COMPANY, OF CHICAGO, ILLINOIS, A CORPORATION OF MAINE

BALLAST CAR

Application filed November 15, 1928. Serial No. 319,506.

This invention relates to dump cars and particularly to improvements in the construction and arrangement of the hoppers, control doors and shedding surfaces therefor, where-
5 by the discharge of material is directed in a predetermined manner. The present invention is illustrated as embodied in a ballast car but it is to be understood that the invention may be equally applicable to other
10 forms or types of hopper cars.

An object of this invention is to provide a control door for the hoppers which is capable of closing to shut off the flow of the lading during the discharge operation while the ma-
15 terial is flowing out through the discharge opening, whereby a portion only of a complete load may be discharged and the remaining portion retained in the car.

Another object of this invention is to pro-
20 vide an improved hopper car construction, which when embodied in a ballast car, is capable of discharging ballast material both in-
wardly and outwardly of the rails, without
danger or liability of flooding the rails.

25 The present disclosure is given merely by way of example and is not to be considered as limiting the invention in any regard, but merely as one embodiment thereof, and the scope of the invention will be determinable
30 from an understanding of the present disclosure as an embodiment thereof, and with a recognition of the advantages which the invention produces in the illustrated embodiment.

35 Further and other objects will appear as the description proceeds.

Referring to the drawings:

Figure 1 is a side elevational view in cross-
35 section of one-half of a dump car constructed
40 in accordance with the present invention.

Figure 2 is a transverse cross sectional view
of the car shown in Figure 1.

The present invention is shown as em-
bodied in a car having the usual underframe,
45 comprising a center sill and cross sills, and
having between the trucks on each side of the
center sill a longitudinally extending hop-
per. Each hopper is provided with oppositely
inclined floor or shedding surfaces spaced
50 at their lower ends to provide a discharge

opening with a pivoted door, adapted to
swing to either side of its center closed posi-
tion so that the material may be unloaded to
the outer side of the rail when the doors are
swung open in one direction, or unloaded be-
55 tween the rails when the doors are swung open
in the other direction.

Referring now to the figures of the draw-
ings, it will be noted that the car 1 is provid-
ed with side walls 2 and a sloping end wall or
floor 3. The center sill 4 comprises the I-beam
4' and extends longitudinally thereof, sup-
ported on the bolster and truck construction
not shown. The hoppers located on each side
of the center sill 4 comprise the oppositely
inclined floor or shedding surfaces 5 and 6
spaced at their lower ends to form a discharge
opening 7. The discharge opening of each
hopper is controlled by a door 8, which in
shape is that of a sector of a cylinder and
which will hereinafter be described as being
of cylindrical-sectoral shape. The doors are
provided at their vertices with a shaft 9
which is pivoted at 10 and 11 in suitable bear-
ings so that by rotation of the shaft, the doors
are swung around the center of the shaft
as a pivot. Each door comprises the upper
arcuate surface 12 and radial surfaces 13
and 14. The door is of such size and shape
that the surface 12 completely closes the dis-
charge opening 7 when the door is in its cen-
tral position, as shown at the lefthand hopper
of Figure 2, but is capable of being swung to
either side of the central closed position
70 whereby a free discharge opening is provid-
ed for the material from the hopper.

Each shaft 9 is provided with a worm gear
15, which is in mesh with the worm 16, car-
ried by the shaft 17. The shaft 17 is mount-
ed in suitable brackets 18 and 19, and has pro-
vided at its outer end a manually operable
lever 20. The lever is capable of being con-
nected for turning the shaft, whereby at the
will of the operator a rotary movement may
be imparted to the door shaft 9 for opening
or closing the doors. Positioned below the
shaft 9 and tapering in opposite direction
therefrom, are mounted the independent shed-
ding surfaces 21 and 22. The construction
is so designed that when the doors are moved
85 90 95 100

inwardly from the closed position the material which is permitted to flow through the discharge opening by such opening of the door, first flows upon the radial surface 14 of the door by which it is guided on to the independent and lower shedding surface 21, whereby the discharge material is directed outside of the rails on which the car runs.

Conversely, when the doors are moved outwardly from the closed position, the shedding surface 13 of the door deflects the material on to the independent shedding surface 22 whereby it is discharged inwardly of the rails. The independent shedding surfaces 21 and 22 for all of the hoppers are preferably fixedly mounted and of such length that lower ends lie substantially in lines A and B, as shown in Figure 2 of the drawing. These lines represent the position of a pile of ballast or other material of known characteristics, as it will lie as deposited or discharged under the influence of gravity from the shedding surfaces 21 or 22, attention being directed to the fact that the lines are limited by portions of the rails upon which the car is mounted below the tops of the rails, and are disposed at the angle of repose of the particular lading for which the car is designed.

In some instances it may be preferable to adjustably mount the shedding surfaces 21 and 22, but for any particular adjustment the surfaces are rigid with relation to the car body. Accordingly, it will be appreciated that the surfaces 21 and 22 have a predetermined and final directing influence on the discharge material from the hoppers, and it will be further realized that the door, irrespective of the direction of opening, presents shedding surfaces which bridge the space between the end of the hopper shedding surfaces and the independent shedding surfaces, such that a substantially continuous shedding surface is provided for deflecting the material either inwardly or outwardly of the rails as desired.

Another important factor is that the door having its surface 12 for closing the discharge opening pivots around the shaft 9, which causes the surface 12 to traverse the path of flow of material substantially transversely therethrough. This renders it possible to intercept the flow of material during discharge and to completely stop or shut off the discharge of a particular hopper before it is completely emptied. This, of course, is attributable to the fact that the force necessary to close the door does not have to lift a portion at least of the weight of the downward flowing material, nor to oppose by a counter movement the inertia of the moving mass in discharge. The cutoff action being substantially transverse to the flow in all portions of its closing movement, avoids the opposition of the forces which would hinder the closing operation.

From the above description it will be appreciated that the present invention accomplishes the above stated objects, together with other objects apparent from an understanding of the disclosure.

The present disclosure is given merely by way of illustration and is not to be considered as limiting the invention, the scope of the invention being clearly set forth in the appended claims.

I claim:

1. In a car of the character described, having a center sill, a longitudinally disposed hopper on one side of said center sill, said hopper having oppositely inclined shedding surfaces spaced at their lower ends to provide a discharge opening, an independent shedding surface below and spaced from said hopper shedding surface, said independent shedding surface being of such length that its lower edge will lie in a line limited by portions of the rails upon which the car is mounted below the top of said rails, which lines are disposed in the angle of repose of the lading for which said car is designed, and a door for said discharge opening for controlling the passage of lading therethrough, said door providing in its open and intermediate positions a shedding surface for directing the discharge lading from said hopper onto said independent shedding surface.

2. In a car of the character described, having a center sill, substantially V-shaped hoppers on each side of the center sill having discharge openings at their bottoms, a pair of independently mounted shedding surfaces located below and spaced from each hopper, the surface of each pair being adapted to direct the discharge of material in opposite direction, each of the shedding surfaces of said pairs of independent shedding surfaces being of such length that their lower ends lie substantially in lines limited by portions of the rails upon which the car is mounted below the tops of the rails, which lines are disposed at the angle of repose of the lading for which the car is designed, and doors for controlling the discharge of material from said hoppers having portions serving as shedding surfaces in the open and intermediate positions of said doors for directing the discharge of lading onto the said independent shedding surfaces, each door being adapted to open in either direction from the center closing position whereby the lading from each hopper may be discharged at will, either inwardly or outwardly of the rails.

3. A car of the class described, having a center sill, a longitudinal V-shaped hopper on each side of said center sill, said hoppers having discharge openings in their bottoms, a stationary deflector of inverted V-shape disposed below each hopper, the shedding surfaces of which deflectors are so disposed as to discharge lading either between the

rails or outside of the rails at lines in the angle of repose of such lading, and swinging doors controlling the discharge of lading from the hoppers, said doors being pivoted on an axis below the hoppers and adapted to swing toward either side of the hoppers to discharge the lading.

5 Signed at Chicago, Illinois, this 7th day of November, 1928.

10 DAVID HINDAHL.
